UNITED STATES PATENT OFFICE.

ALFRED H. DAVIES, OF AKRON, OHIO, ASSIGNOR TO BENJ. F. JOHNSON AND WILLIAM WARD, BOTH OF CLEVELAND, OHIO.

GAS-HEATED SAD-IRON.

1,076,958.

Specification of Letters Patent.

Patented Oct. 28, 1913.

Application filed February 17, 1911. Serial No. 609,220.

To all whom it may concern:

Be it known that I, ALFRED H. DAVIES, a citizen of the United States, residing at Akron, in the county of Summit and State 5 of Ohio, have invented a new and useful Gas-Heated Sad-Iron, of which the following is a specification.

My invention relates to improvements in sad irons heated by means of gas conducted 10 to said irons through a suitable, flexible tube.

The objects of my invention are to generally improve sad irons of the character mentioned and to provide such construction that 15 the heat from the iron body will not be transmitted to the mixer, to the metal parts connected therewith and to the flexible tube connection.

In many gas heated sad irons heretofore 20 constructed a common fault has been that the heat from the iron body has been transmitted to the mixer, the metal parts connected thereto, and the flexible tube connection, in some cases even melting the flexible 25 tube connection, thus causing annoyance, damage and great danger. By my invented construction I propose to avoid these undesirable features.

The objects above noted, together with 30 other objects readily apparent to those skilled in the art, I attain by the construction illustrated in the accompanying drawings, although my invention may be embodied in other forms, the construction illustrated being chosen by way of example.

In the drawings Figure 1 is a perspective view of a gas heated sad iron embodying my invention. Fig. 2 is a side elevation of the iron handle, cover, burner and the 40 mixer and its related parts. Fig. 3 is a transverse vertical sectional view of the cover and burner. Fig. 4 is a longitudinal vertical sectional view of the mixer.

Throughout the several views similar reference numerals indicate similar parts.

The numeral 1 indicates the hollow iron body preferably of the form shown in the drawing and having a cut away portion at 2 in its rear wall 3. The body 1 is open at 50 the top, the walls of said body being provided with the upper edge 4. For the purpose of closing the top of said body 1 the cover 5 is provided, which cover extends from side to side across the top of the body 55 1 and is provided with the spaced depending

lugs 6 adapted to rest upon the edge 4 for the purpose of spacing the cover proper from said edge to permit the exhaust of burned gases from the interior of the body.

Formed integrally with the cover 5 is the burner portion 7 which consists of a tubular structure running longitudinally under the cover 5 and spaced therefrom as at 8, said burner being connected to the cover 5 by integral connecting portions 9 and 10 at the 60 front and rear ends respectively.

The burner 7 on its lower side is provided with the transverse slots 11 through which the mixed gas and air may pass from the interior of the burner into the interior of the 70 body of the iron. The burner 7 is closed at its front end but is open at its rear end as shown at 12 in Fig. 1. The cut away portion 2 is adapted to receive the burner 7 and connecting portion 10 so that the rear end of 75 the burner 7, when the parts are operatively arranged, will be substantially flush with the external surface of the rear wall 3. The cover 5 is connected to the body 1 by means of the screws 13 or other equivalent means. 80

Mounted upon the cover 5 and held in spaced relation thereto by the spacing lugs 14 is the handle shield 15 which is connected to the cover 5 by the screw 16 or its equivalent. Preferably formed integrally 85 with the handle shield 15 are the forward and rear handle uprights 17 and 18 respectively to which the handle 19 is connected by means of the bolt 20. The handle shield 15, being spaced from the cover 5, air will 90 be permitted to circulate between said cover and handle shield, thus permitting the operator to hold the handle 19 in the hand without experiencing inconvenience from heat radiation from the said cover. 95

The mixer 21 and the supporting member 22 are preferably formed integrally. The member 22 is connected at its upper end to the handle upright 18 by means of the bolt 20 and extends downwardly and curves rearwardly to the mixer 21. The said mixer consists of a hollow funnel shaped portion 23 provided at its base with air inlet openings 24 which are formed between the edges of the portion 23 at its base or rear end and the base 25 of the supporting member 22 which extends vertically across the base of the mixer as shown in Figs. 1 and 4. The smaller forward end of the mixer provided with the exhaust opening 26 is spaced from 110

the rear wall 3 and the rear end of the burner 7 and is so disposed as to direct the gas and air from said mixer into the interior of the burner 7 through the rear opening 12. 5
5 Mounted upon the base portion 25 of the supporting member 22 is the gas valve casting 27 which is provided with a screw 28 having a needle point 29 which co-acts with the conical walls of the aperture 30 to form 10 a needle valve so that by adjustment of the screw 28 more or less gas will be permitted to enter the mixer through said aperture 30, as may be desired. For supplying gas to the gas valve a metallic tube 31, prefer- 15 ably arranged parallel with the supporting member 22, is connected by the screw threads 32 to the part 27 and a flexible tube 33 for conducting gas to the tube 31 is provided. It will be understood that the gas conducted 20 by the tube 33 will pass through the tube 31 and the interior of the gas valve casing, being projected forwardly through the aperture 30 and the interior of the mixer 21 into the interior of the burner 7, whence said 25 gas, with the air drawn in through the mixer, will pass through the slots 11, distributing the flame along the bottom of the interior of the iron body 1 from front to rear thereof. 30
30 It should be especially noted that in so far as any heat may be conducted through the metal to the tube 33 or its connection, such heat will of necessity have to pass through the lugs 14 or screw 16, the handle 35 upright 18, the supporting member 22, the mixer and the tube 31 before reaching the flexible tube 33 or its connection to the tube 31. It will be readily apparent to those skilled in the art that very little heat will 40 thus reach the tube 33, and as the gas and air are being continually drawn in through the mixer 21 and projected into the interior of the burner, very little heat will be transmitted from the burner or iron body itself 45 to the mixer, across the intervening space,

and that any heat that may be thus conducted will be largely counteracted by the inrush of air through said mixer. In this way the mixer, the metal parts connected therewith and the flexible tube connection 50 will be maintained at a comparatively low temperature, thus avoiding the annoyance, damage and danger heretofore commonly attendant upon the use of gas heated sad irons. 55

I claim:—

In a gas heated sad iron, in combination with a hollow iron body provided with vertical walls, one of said walls provided with a cut away portion, a cover extending across 60 the top of the body and provided with spaced lugs adapted to rest upon the top edge of the side walls, a burner portion connected to the cover at its front and rear ends and downwardly spaced therefrom in intermediate said ends, the rear end of said burner being adapted to be received into the said cut away portion and provided with an external opening at the rear end, a handle shield connected to said cover and spaced 65 therefrom by means of spacing lugs, a handle connected to said handle shield, a mixer supporting member connected to the rear end of said handle and extending rearwardly and downwardly to a point out- 70 wardly spaced from and directly opposite said external opening, a mixer connected to said mixer supporting member and adapted to mix air and gas and project the same through said external opening into the in- 75terior of said burner and means for conducting gas to said mixer. 80

In testimony that I claim the above, I have hereunto subscribed my name in the presence of two witnesses.

ALFRED H. DAVIES.
